UNITED STATES PATENT OFFICE.

HENRY C. McBURNEY, OF LOS ANGELES, CALIFORNIA.

REFUSE-COLLECTING BAG.

1,228,333.

Specification of Letters Patent. Patented May 29, 1917.

Application filed November 20, 1915. Serial No. 62,546.

To all whom it may concern:

Be it known that I, HENRY C. McBURNEY, a citizen of the United States, residing at Los Angeles, in the county of Los Angeles 5 and State of California, have invented certain new and useful Improvements in Refuse-Collecting Bags; and I do hereby declare the following to be a full, clear, and exact description of the invention, such as 10 will enable others skilled in the art to which it appertains to make and use the same.

The primary object of this invention is to provide a novel type of bag, for collecting refuse, which bag can be suspended from 15 a suitable support and have the mouth thereof held open so as to admit of the collected matter being deposited therein.

Another object of the invention is to provide a bag for carrying out the above objects, and of such construction that the bag can be placed in a horizontal position on the ground, floor, or other surface, and have the mouth thereof so disposed that the collected refuse can be conveniently deposited 25 within the bag.

Other objects will appear and be better understood from that embodiment of my invention of which the following is a specification, reference being had to the accompanying drawings forming a part thereof in which:—

Figure 1 is a vertical elevation of the bag, showing the same suspended from a vertical support.

Fig. 2 is a longitudinal section taken through the bag when the same is placed in horizontal position.

Fig. 3 is a perspective view of a wire frame employed to hold the mouth of the bag in 40 opened position.

Referring to the drawings in detail, the numeral 1 designates a bag, formed of fabric, and having an opened mouth 2, the edge of the mouth being turned inwardly 45 and secured to the side walls of the bag, to provide a hem 3.

Associated with the mouth of the bag is a circular frame adapted to hold the mouth of the bag opened. This frame is located 50 within and extends around the hem 3 and is formed of a single length of wire bent in-

termidate its ends to provide a substantially L-shaped loop having the arms 4 and 5. The strands of the wire are continued from the arms 5 of the L-shaped loop, and crossed at 55 a point 6 and continued therefrom and formed to provide a concentric ring 7, the opposite ends of the strands being arranged in overlapped relation, as shown at 8 in Fig. 3 of the drawing. The frame is so constructed that it can be adjusted to accommodate bags of different diameters. 60

When it is desired to have the bag in upright position, during the depositing of the collected material therein, the L-shaped loop 65 is engaged over the vertical support 9 as shown in Fig. 1 of the drawing. When the loop is so engaged over the support 9, the weight of the bag 1 will cause the arm 4 thereof to bind against the support 9, and hold the bag against longitudinal movement on the support. When the bag 1 is placed in horizontal position, the arm 4 is forced 70 downwardly into parallelism with the surface upon which the bag rests, by one foot 75 of the operator, resulting in the mouth of the bag being moved upwardly to the position shown in Fig. 2, so as to admit of the refuse being conveniently deposited within the bag. 80

Having thus described my invention what I claim as new is:—

In combination with a bag having a circular pocket at the mouth thereof, one wall of the pocket having an opening therein, of 85 a frame formed of a single length of wire bent at a point intermediate its ends to provide an L-shaped looped portion, the ends of the wire being continued from the horizontal arm of the looped portion and intersected and extended through the opening in the wall of the pocket, the said ends of the wire being curved from their point of intersection and extended around the pocket 90 in the bag and having their terminals overlapped, for the purpose specified. 95

In testimony whereof I affix my signature in presence of two witnesses.

HENRY C. McBURNEY.
